C. P. PETERSON.
SAD IRON POLISHING MACHINE.

No. 538,743.

Patented May 7, 1895.

C. P. Peterson

Inventor

UNITED STATES PATENT OFFICE.

CHARLES P. PETERSON, OF RIDGEDALE, TENNESSEE.

SAD-IRON-POLISHING MACHINE.

SPECIFICATION forming part of Letters Patent No. 538,743, dated May 7, 1895.

Application filed December 20, 1893. Serial No. 494,236. (No model.)

To all whom it may concern:

Be it known that I, CHARLES P. PETERSON, a citizen of the United States, residing at Ridge-
dale, in the county of Hamilton and State of
Tennessee, have invented a new and useful Im-
provement in Sad-Iron-Polishing Machines,
of which the following is a specification, ref-
erence being had to the accompanying draw-
ings.

10 My invention relates to grinding and pol-
ishing machines, and particularly to devices
for dressing sad-irons, the objects in view be-
ing to provide a simple and efficient device
for grinding the working or polishing sur-
15 faces of sad-irons in the course of their manu-
facture; and with this object in view the in-
vention consists in a certain novel construc-
tion, combination, and arrangement of parts
fully described hereinafter in connection with
20 the accompanying drawings, and particularly
pointed out in the appended claims.

In the drawings, Figure 1 is a sectional
view of a machine embodying my invention.
Fig. 2 is a horizontal section of the same on
25 the line 2 2 of Fig. 1. Fig. 3 is a vertical sec-
tion of a slightly-modified form of the ma-
chine. Fig. 4 is a detail view, in perspective,
of one of the grinding and polishing blocks.

Similar numerals of reference indicate cor-
30 responding parts in all the figures of the draw-
ings.

I designates a supporting frame, in which
are mounted the vertical spindles 2, said spindles
being concentric with openings 3 formed
35 in a horizontal platform 4 supported in the
framework. Carried by these spindles 2
slightly below the plane of said platform are
rotary grinding wheels 5 having rims 6, which
are channeled upon their upper sides, as
40 shown at 7, for the reception of grinding or
polishing blocks 8 of emery or other suitable
abrasive material. These grinding and pol-
ishing blocks 8 are segmental in shape and
are independently removable from the chan-
45 neled supporting wheels, whereby one of the
segmental sections or blocks may be replaced
without affecting the others when worn or
injured.

Secured to the platform 4 around the open-
50 ings 3 therein are series of fixed holding arms
9, with which are engaged the irons 10, which
rest upon the upper surfaces of the grinding

and polishing blocks. These holding arms
maintain the irons from rotation with the
grinding and polishing wheels. 55

Secured to the vertical spindles 2 slightly
above the plane of the channeled rims of the
wheels 5 are the agitating arms 11, which ex-
tend radially from the spindles and consist of
a slotted block 12 having a terminal spring 60
12^a to engage the side surfaces of the irons
successively during the rotation of the spin-
dles to give a vibratory motion to the irons
to bring their lower surfaces into contact
with different parts of the grinding surfaces 65
of the blocks 8 to avoid grooving or chan-
neling such blocks. These agitating arms
are slotted to receive the spindles and are
secured to the spindles by means of nuts 13,
or similar devices. The means for operating 70
said vertical spindles 2 may be varied as
desired, but in the construction shown in Fig.
1, said means consist of a driving-shaft 14
mounted in bearings 15 and carrying a belt-
pulley 16, and intermeshing beveled gears 17 75
and 18 fixed respectively to the extremities
of the driving shaft and the upper ends of the
spindles.

In the construction illustrated in Fig. 3 the
operating mechanism is more simple in con-
struction and is adapted especially for use in
connection with a machine in which only one
grinding wheel is employed, in which case the
belt-pulley 16 is attached directly to the spin-
dle 2, the upper end of the latter being mount- 85
ed in a bearing 19 in an overhanging or su-
perjacent beam 20.

This being the construction of the improved
mechanism the operation thereof, briefly
stated, is as follows: The irons are placed with
their operating or polishing surfaces upon
the grinding blocks supported by the wheel,
the rear ends of said irons being engaged by
the holding arms 9, which are provided with
terminal shoulders 21 to prevent lateral dis-
placement, and the spindle 2 is rotated to
cause a rotary movement of the wheel. As
the agitating arm 12 engages the irons suc-
cessively, it pushes the smaller or reduced
ends of said irons outward or toward the pe- 95
riphery of the wheel. The rotation of the
wheel has a tendency to move said smaller
or reduced ends of the irons inward or toward
the center of rotation, and hence the regular 100

vibration of the irons during the operation of the machine.

It will be understood that in practice various changes in the form, proportion, and 5 the minor details of construction may be resorted to without departing from the spirit of the invention or sacrificing any of the advantages thereof.

Having described my invention, what I 10 claim is—

1. In a machine of the class described, the combination of a horizontally disposed wheel provided with a channeled rim, grinding blocks fitting in said channeled rim, means 15 for holding irons from rotation with the wheel while their lower surfaces are in contact with said grinding-blocks, a radial agitating arm mounted at concentric with and above the plane of the wheel and having its outer end 20 arranged in position to engage the irons supported by the wheel, and means for rotating said wheel and agitating arm, substantially as specified.

2. In a machine of the class described, the combination with a supporting framework, 25 of a vertical spindle mounted in bearings therein, a wheel fixed to the said spindle and provided with a channeled rim, separable segmental grinding blocks arranged in said channeled rim, stationary holding arms arranged above the plane of the wheel to engage and hold irons from rotating with the wheel, an agitating arm fixed to the spindle and having a terminal spring arranged with its outer free end in position to engage the 35 irons successively during the rotation of the spindle, and means for operating the spindle, substantially as specified.

In testimony that I claim the foregoing as my own I have hereto affixed my signature in 40 presence of two witnesses.

C. P. PETERSON.
